UNITED STATES PATENT OFFICE

WILLIAM A. BOLLINGER, OF PITTSBURGH, PENNSYLVANIA

HEATING APPARATUS

Application filed March 10, 1930. Serial No. 434,530.

My invention relates to certain new and useful improvements in a heating apparatus, somewhat of the class disclosed in my co-pending application for Letters Patent of the United States, bearing filing date the 5 22nd day of June, 1928 and Serial No. 287,616, and while primarily intended for heating apparatus of the hot air type, it is to be understood that the principle of the invention may be embodied in any other type 10 of heating apparatus wherein it is found to be applicable.

Important objects of the invention are to provide a heating apparatus of the character described, which will supply greater heat on relative fuel consumption, by utilizing and consuming the products of combustion while the latter is passing from the combustion chamber to the flue or chimney; which provides for the upward travel of the products of combustion therethrough to stimulate combustion and enhance its efficiency; which is simple in its construction and arrangement, durable and efficient in its use, and comparatively inexpensive to manufacture, maintain and operate.

With the foregoing and other objects in view which will appear as the description proceeds, the invention resides in the combination and arrangement of parts and in the details of construction hereinafter described and claimed, it being understood that changes in the precise embodiment of the invention hereinafter disclosed can be made within the 35 scope of what is claimed without departing from the spirit of the invention.

In the drawings wherein like numerals of reference designate corresponding parts throughout the several views:

Figure 1 is a side elevational view, partly in cross section, of a heating apparatus constructed in accordance with the invention.

Figure 2 is an end view thereof.

Referring in detail to the drawings my 45 improved heating apparatus comprises a hot air radiator manifold consisting of an outer end casing 2, an inner end casing 3, and a plurality of conductor pipes, respectively indicated at 4, 5, 6, 7, 8 and 9. The casing 2 and 50 3, and the conductor pipes 4, 5, 6, 7, 8 and 9

are preferably rectangular in transverse cross section to afford greater radiating surface, but it is obvious that the contour of the said casings and conductor pipes may be varied to best meet conditions found in practice.

The outer end casing 2 is disposed vertically and provided with a pair of transversely extending partitions 10, which divide the casing 2 into three separate compartments, respectively indicated at 11, 12 and 13.

The inner end casing 3 is likewise disposed vertically and provided with a transversely extending partition 14, which divides the casing 3 into two separate compartments, indicated at 15 and 16.

The casings 2 and 3 are each provided with a plurality of opening flanges 17, two of which respectively establish communication with each of the compartments 11, 12, 13, 15 and 16. The ends of the conductor pipes 4, 5, 6, 7, 8 and 9 overlap and are attached to respective opening flanges 17 in the following arrangement: The outer ends of the conductor pipes 4 and 5 communicate with the casing compartment 11; the outer ends of the conductor pipes 6 and 7 communicate with the casing compartment 12; and the outer ends of the conductor pipes 8 and 9 communicate with the casing compartment 13. In like manner, the inner ends of the conductor pipes 5 and 6 communicate with the casing compartment 15, and the inner ends of the conductor pipes 7 and 8 communicate with the casing compartment 16.

A furnace structure 18, providing a combustion chamber 24, is joined with the inner end of the radiator manifold 1, and encloses the compartment casing 3, which virtually constitutes the inner wall of the furnace structure 18. The latter includes a front wall 19, side walls 20 and 21, and a bottom 22. The conductor pipe 4 projects through the furnace structure 18 and provides a top 23 for the latter, having its end closed by the front wall 19.

The top of this projecting portion of the conductor pipe 4 is provided with an opening flange 25 connecting with a flue pipe 26, which joins with a stack or chimney for 100

stimulating combustion and ultimately dissipating the products of combustion.

A burner element 27 of any suitable construction is mounted in the combustion chamber 24, and it is obvious that the latter may be constructed to accommodate the same to the use of any kind of fuel.

A vertically disposed partition wall 28, mounted in the combustion chamber 24, is fixedly connected to and supported by the furnace side walls 20 and 21. The partition wall 28 extends transversely through the combustion chamber 24 and has its upper end spaced from the top 23 of the latter. The partition wall 28 is disposed adjacent to the inner end casing 3, thereby providing a passage 29 therebetween. The lower end of the latter communicates with the inner end of the combustion pipe 9, as indicated at 30.

The conductor pipes 4, 5, 6, 7, 8 and 9 have their respective side walls disposed on the same vertical plane and are superposed relatively to each other, in the sequence enumerated. The conductor pipes 4, 5, 6, 7, 8 and 9, while extending approximately in a horizontal direction, are disposed angularly to incline slightly from the horizontal position, and the angular disposition of any of the conductor pipes is directly opposed to the angular disposition of the conductor pipes adjacent thereto.

The conductor pipes 4, 6 and 8 are disposed parallel to each other and incline toward the furnace structure 18, while the alternate conductor pipes 5, 7 and 9 are disposed parallel to each other and incline toward the outer end casing 2. The angular disposition of the conductor pipes 4, 5, 6, 7, 8 and 9, in the manner stated, is uniform and permits the constant upward travel of the products of combustion from the time that the latter enter the radiator manifold 1 from the combustion chamber through the communicating passage 30, until the products of combustion are dissipated through the flue pipe 26.

The heating apparatus is mounted on a base 31, of any suitable construction for supporting the device in spaced relation to the floor on which it rests.

It will be apparent, that the casing compartments 11, 12, 13, 15 and 16 merely constitute inter-communicating passageways for suitably connecting the associated conductor pipes to provide a continuous uninterrupted passage from the combustion chamber 24 to the flue pipe 26.

In the operation of my improved heating apparatus, the products of combustion travel through the radiator manifold 1, as clearly indicated by arrows. The products of combustion from the combustion chamber 24 pass downwardly through the combustion chamber passage 29 and outwardly through the lowest conductor pipe 9, through the compartment 18, inwardly through the conductor

pipe 8, through the compartment 16, outwardly through the conductor pipe 7, through the compartment 12, inwardly through the conductor pipe 6, through the compartment 15, outwardly through the conductor pipe 5, through the compartment 11, and inwardly through the top conductor pipe 4, from where it is dissipated through the flue pipe 26 in a stack or chimney.

The purpose of the partition wall 28, in the combustion chamber 24, is to direct the travel of the products of combustion from the burner element 27 against the furnace top 23, which constitutes an end portion of the conductor pipe 4. As this portion of the latter communicates with the flue pipe 26, it is essential for efficient performance that the same be maintained at a high temperature to promote proper draft action through the radiator manifold 1 and to consume all material products of combustion.

The partition wall 28 further serves to direct the products of combustion against the inner end casing 3 of the radiator manifold 1, as the said products of combustion travel downwardly through the passage 29. By thus heating the casing 3, the products of combustion, on passing through the radiator manifold 1, will be maintained at a high heating temperature and will be accelerated in their travel through the latter, whereby the products of combustion within the radiator manifold 1 will be of the most efficient heating temperature.

It will here be noted that the arrangement, configuration and number of conductor pipes embodied in my improved apparatus, may be widely varied to best meet any conditions found in practice. Further, the construction of the combustion chamber 24 and burner element 27 may be such as to render the same adaptable for the consumption of coal, oil, gas or any other fuel.

The radiator manifold 1 is preferably constructed from sheet material and of a metal best suited for heat radiation. The device may or may not be enclosed in a jacket depending upon whether the same be utilized for local or remote heat distribution.

A feature of the present invention resides in the angular disposition of the conductor pipes 4, 5, 6, 7, 8 and 9, in the manner stated, whereby the travel of the products of combustion therethrough is constantly upward without untoward natural resistance as when attempting to force or draw the products of combustion downwardly against its natural flow by draft action or any other means.

The present invention provides a most efficient heating apparatus, having a relatively high heating capacity on maximum fuel consumption.

What I claim is:

1. In combination, a heating apparatus of the character described, comprising a furnace

structure providing a combustion chamber, a vertically disposed outer end casing divided into a plurality of compartments, a vertically disposed inner end casing divided into a plurality of compartments, said inner end casing extending into said combustion chamber and constituting the inner wall of the latter, a plurality of conductor pipes extending between said outer end casing and said inner end casing and connecting with respective compartments to provide a continuous conduit for the travel of the products of combustion, a vertically extending partition wall mounted in the combustion chamber adjacent to said inner casing and providing a passage for the products of combustion, the inlet end of the lower of said conductor pipes communicating with the lower end of said passage, the upper of said conductor pipes projecting over said combustion chamber and constituting the top of the latter, and a flue element communicating with said projecting portion of said upper conductor pipe, the upper end of said partition wall being spaced from the top of said combustion chamber.

2. In combination, a heating apparatus of the character described, comprising a furnace structure providing a combustion chamber, a vertically disposed outer end casing divided into a plurality of compartments, a vertically disposed inner end casing divided into a plurality of compartments, said inner end casing extending into said combustion chamber and constituting the inner wall of the latter, a plurality of conductor pipes extending between said outer end casing and said inner end casing and connecting with respective compartments to provide a continuous conduit for the travel of the products of combustion, a vertically extending partition wall mounted in the combustion chamber adjacent to said inner casing and providing a passage for the products of combustion, the inlet end of the lower of said conductor pipes communicating with the lower end of said passage, the upper of said conductor pipes projecting over said combustion chamber and constituting the top of the latter, and a flue element communicating with said projecting portion of said upper conductor pipe, the upper end of said partition wall being spaced from the top of said combustion chamber, each of said conductor pipes being disposed at a slight angle from the horizontal plane to cause the continuous upward movement of the products of combustion on its travel through said conductor pipes and through said compartments.

60 In testimony whereof I affix my signature.
WILLIAM A. BOLLINGER.
